UNITED STATES PATENT OFFICE.

JOHN T. McCLOSKEY, OF DAYTON, OHIO.

TOBACCO STEMMING AND BOOKING MACHINE.

1,116,719.

Specification of Letters Patent. Patented Nov. 10, 1914.

Application filed June 8, 1914. Serial No. 843,638.

To all whom it may concern:

Be it known that I, JOHN T. McCLOSKEY, a citizen of the United States, residing at Dayton, in the county of Montgomery and State 5 of Ohio, have invented certain new and useful Improvements in Tobacco Stemming and Booking Machines; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

This invention relates to improvements in machines for stemming and booking tobacco.

The object of the invention is to provide a 20 form of mechanism which reduces to a minimum the risks run by the operator in stemming and booking tobacco. It is well known by those familiar with this work that the operatives are usually girls or women and their lack of adeptness in handling machinery often exposes them to more or less 25 danger, it being a common thing for them to lose a finger or fingers of one or the other hand or otherwise injure the hand in manipulating a machine. To obviate these dangers 30 and to make the work of stemming and booking tobacco comparatively safe for these inexperienced operatives is the principal object of the invention.

A further object is to provide a machine 35 that is not only safe, but which in addition to stemming the tobacco leaves also books said leaves upon the table upon which they are left in the stemming operation and therefore greatly economizes the work of handling 40 tobacco. All parts that are likely to endanger the operatives are eliminated. The machine stems and books the tobacco in one operation and leaves the tobacco ready for use.

45 Preceding a detail description of the invention reference is made to the accompanying drawings of which—

Figure 1 is a top plan view of my improved tobacco stemming and booking machine; 50 Fig. 2 is a vertical sectional elevation of the machine on the line *a—a* of Fig. 1; Fig. 3 is a side elevation of the machine partly in section with parts broken away; Fig. 4 is an enlarged detail view of the carriage and a 55 portion of one of the tracks over which it travels back and forth in the operation of

stemming the tobacco; Fig. 5 is a detail view of the ratchet devices for lowering the work tables for each successive stemming and booking operation; Fig. 6 is an end elevation of the knives and their adjustable supporting means.

In the specification and drawings, similar reference characters indicate corresponding parts.

The frame work of the machine may vary; it is here shown to comprise side supporting members 1 and upper horizontal members 2 united to the side members 1 and also a cross bar 13.

3—3 represents two horizontal parallel stemming knives held a suitable distance apart by distance pieces 4 and supported upon yoke supports 5 through which adjusting screws 6 pass. These adjusting screws 6 engage the distance pieces and maintain the knives in a proper operative position. A work table consisting of two sections 7—7, one of which is mounted on each side of the knives 3—3, is provided for booking and 70 supporting the tobacco. These table sections 7—7 are supported upon aprons 8 and are subject to vertical movement through guides 9 on said aprons which are received by guides 10 depended from the knives 3—3 and 75 attached to the sides of said knives near the ends thereof. This sectional table receives the stemmed tobacco upon which it is booked, and the adjustment or movement 80 thereof is obtained through screws 11 which engage apertured lugs 12 on the aprons of the tables, the lower ends of said screws being provided with bearings in the cross bar 13. The lower ends of said screws 11 have 85 fixed to them bevel gears 14 which mesh with similar gears 15 on a transverse shaft 16 journaled in bearings 61 depending from the cross bar 13 said shaft 16 being provided 90 with a crank 59 by means of which it is rotated to initially elevate the tables 7—7 95 into a working position relative to the other parts of the machine to be described. Mounted above the sectional table and parallel therewith are two clamping wings 26—26 which are adapted to hold the leaves of tobacco in position over the edges of the knives and against the tables 7—7. These wings 100 are attached to parallel shafts 28 arranged at the opposite longitudinal sides of the frame of the machine in bearings 30 and are 105 normally held in upright positions as shown in the dotted position in Fig. 2. The said

wings are so held by springs 29 which are coiled about shafts 28 and are so arranged as to exert an upward force upon the said wings to hold them in such elevated positions. The said clamping wings are maintained in their lowered positions, as shown in Figs. 1 and 2, by means of crank arms 32 fixed to the ends of the shafts 28 and to which are connected rods 33 extending down and connecting with a common foot treadle 34 supported upon a shaft 25 mounted in the lower portion of the frame work of the machine.

As shown in Fig. 1, the clamping wings 26 have portions thereof cut away as at 27 to provide spaces for the arms of the operator to rest upon while the work of stemming and booking the tobacco proceeds. In advance of the clamping wings 26 are arranged two clamping bars 17 also above the work tables 7-7 and which initially engage the pointed ends of the tobacco leaves and hold the same in position while the hands of the operator spread the remaining parts of the leaves upon the tables 7-7 and before the clamping wings 26 are lowered upon the other portions of the leaves. One of these clamping bars 17 lies on each side of the knives 3-3 and ends thereof are fixedly attached to a shaft 18 mounted in bearings 19 on the frame of the machine. The lower sides of said clamping bars 17 are provided with rubber tips 20 the purpose of which is to insure a proper engagement with the tobacco leaves after the same have been placed in position over the knives 3-3. The position of each tobacco leaf is such that the rib or stem thereof lies over the space between the knives so that when the leaf is cut the stem or rib removed therefrom through the cutting operation, falls within a receptacle 60 mounted on the frame-work of the machine. The initial clamps 17-17 are normally held in the lower position, as shown in Fig. 3, by a coil spring 22 one end of which is attached to a crank arm 21 fixed to the shaft 18 and the other end of which is attached to a suitable part of the frame-work of the machine as is clearly shown in Fig. 3. The crank arm 21 is connected with the rod 23 which extends down to a foot-treadle 24 mounted adjacent to the foot-treadle 34 on the shaft 35. The foot-treadle 24 is manipulated each time a tobacco leaf is placed in position on the tables 7-7 and over the knives 3-3 to raise the clamps 17-17 from the position shown in Fig. 3. This position, it will be understood, is the position in which the clamps 17-17 are when they are initially holding the ends of the tobacco leaves in position to be spread upon the tables. Cutting rollers 35, of which there are two, travel over the longitudinal edges of the knives 3-3. These rollers are journaled in a frame 36 from

which extend pins 37 through a frame 38 the latter frame being mounted upon a cross bar 39 which lies between and is connected to two roller carriages 41. The stems 37 of the rollers 35 are provided with coil springs 40 which exert a pressure to maintain the said rollers in proper position above the knives. While I have shown two such rollers 35, a single roller may serve the purpose, two rollers, however, being preferable. The carriages 41 to which the roller bar 39 is attached is provided with rollers 42 which move horizontally on lower tracks 43 said tracks having grooves 62 in which the rollers 42 fit. The tracks 43 are mounted on the upper portion of the frame at each side of the machine and above said tracks 43 are upper parallel tracks 44 which are united to the lower tracks 43 by end posts 45. These upper tracks 44 are alining tracks for the roller carriages and upper guide rollers 46 engage said upper tracks. The guide rollers 46 are mounted upon stems 47 in bearings 48 and a spring 49 exerts force to maintain said rollers 46 in proper engagement with the upper tracks. Attached to the median portion of the cross bar 39, which as before stated is united at its ends to the roller carriages 41, is a link 51 pivotally united to the cross bar 39 by means of a pivot extending through apertured ears 50 united to said cross bar. This cross bar 39, it will be borne in mind, supports the rollers 35 which move over the edges of the knives 3-3 and stem the tobacco leaves. The connecting link 51 is pivoted at 52 to an angular lever 53 which extends down and is fixedly united to a shaft 54 journaled in the upright side members 1-1 of the frame. Also united to the shaft 54 on one side of the frame and adjacent to the lever 53 is an operating lever 55 by means of which the shaft 54 is rotated sufficiently to cause the lever 53 and the connecting link 51 to move the roller carriages over the tracks 43 and therewith the stemming rollers 35 the length of the knives 3-3. This operation severs the stems from the tobacco leaves and allows the leaves to book upon the tables 7-7 while the stems, as before stated, fall through the space between the knives into the receptacle 60. The return movement of the operating lever 55 lowers the tables 7-7 a distance corresponding approximately to the thickness of a leaf of tobacco in order to prepare said tables for each succeeding leaf to be stemmed and booked. This table-lowering mechanism is illustrated in Figs. 2 and 5 and consists of a ratchet pawl 56 which is slidably mounted on the inner side of the lever 55 in a position to engage the ratchet wheel 57 which is fixed to the shaft 16. The said pawl 56 drops into the teeth of the ratchet 57 by gravity. It is supported upon the lever 55 by two head studs which are shown in Fig. 130

6. The pawl is provided with two slightly elongated openings through which the studs pass. There is also pivoted to the frame of the machine a detent or gravity pawl 58 which is adapted to engage the ratchet 57 to prevent any backward movement thereof under the engagement of the actuating pawl 56. When the operating lever 55 is moved back to the position shown in Fig. 3, this 10 operation of the shaft 16 takes place to lower the tables 7-7 as hereinbefore stated.

Briefly describing the operation of the machine, reference is made to Fig. 1. The operator sits in front of the table and applies the tobacco leaves to the tables 7-7 with the stems thereof over the knives 3-3. At this time the wings 26-26 are elevated by the action of the springs 29 and the clamping bars 17-17 are elevated by the operator's foot pressing upon the treadle 24. After the leaf has been placed in position with the pointed end thereof under the clamps 17-17, the foot is removed from the treadle 24 and the spring 22 draws the 25 clamps 17-17 down against the end of the leaf. The remaining portion of the leaf is then spread out by the hands of the operator and foot pressure is applied to the foot treadle 34 to lower the clamping wings 30 26-26 upon the leaf thus spread out upon the tables 7-7. The hand of the operator then grasps the lever 55 and moves it forward to cause the cutting rollers 35 to move over that portion of the leaf immediately above the edges of the knife. This operation being performed, the lever 55 is returned to its normal position and the tables 7-7 are lowered sufficiently to permit of the next leaf being placed in position for stemming and 40 45 booking and this operation is continued until the tables receive a full supply of tobacco stemmed and booked.

While I have with some minuteness described various details of construction, I do not wish to limit myself to any detail which may be varied without departing from the spirit of the invention. It will also be apparent that the reciprocable stemming mechanism may be operated by power as well as 50 manually, and that automatic means may be employed to lower the tables 7-7 at the completion of every operation of the shaft 54; and other details may be varied without departing from the spirit and underlying 55 principles of the invention.

Having described my invention, I claim.

1. In a machine of the character specified, the combination with a table for supporting tobacco leaves, and means for elevating the 60 same, of knives arranged centrally of said

table and parallel thereto, and between which the stems of the tobacco leaves lie, and clamping members one hinged on each side of the knives adjacent to the front ends thereof and arranged to hold the pointed ends of the tobacco leaves in position while said leaves are being spread upon the table.

2. In a machine of the character specified, the combination with a table upon which tobacco leaves to be stemmed and booked are placed, and means for elevating said table, of knives arranged centrally relative to said table and between which the stems of the tobacco leaves lie, clamping devices comprising hinged plates arranged to initially hold said leaves in such position, a cutting roller adapted to move over said knives to cut the stems from the tobacco leaves, oppositely arranged carriages upon which said roller is carried, and means for actuating said carriage to so move the roller over the knives.

3. In a machine of the character specified, the combination with a table consisting of two sections upon which tobacco leaves are stemmed and booked, of knives arranged between said table sections and between which the stems of the tobacco leaves lie, hinged clamping members arranged to initially hold the pointed ends of the tobacco leaves firmly against said table sections, clamping wings arranged to subsequently engage the leaves on the sides of the knives to hold them against the table sections, and a cutting roller adapted to move over said knives to sever the stems from the leaves.

4. In a machine of the character specified, the combination with a table comprising two sections upon which the tobacco leaves are supported during the stemming operation and upon which the stemmed leaves are packed or booked, and means for adjusting said table vertically, of knives arranged parallel with said table and centrally thereof, means for adjusting the position of said knives, initial clamping members arranged to clamp the ends of the tobacco leaves upon said table over said knives, said initial clamping members being stationary relatively to the pointed ends of said leaves, and clamping wings, adapted to subsequently hold the leaves against the table during the operation of stemming, and pack or book the stemmed leaves on said table.

In testimony whereof I affix my signature, in presence of two witnesses.

JOHN T. McCLOSKEY.
